AIRPLANE

Byron B. Phillips, Stuyvesant Falls, N. Y.

Application May 11, 1933, Serial No. 670,601

7 Claims. (Cl. 244—18)

This invention relates to improvements in airplanes.

As is well known, the forces which sustain an airplane in flight are due to the relatively low and high pressures existing respectively above and below the ship, and such sustaining differential pressures are dependent upon relatively rapid forward movement of the plane. It obviously is desirable to provide an airship of the heavier-than-air type wherein rapid forward movement is unnecessary to sustain flight, inasmuch as landing and taking-off are greatly facilitated and much smaller landing fields are required. While improvements in airplane principles and design 10 have provided ships which do not require relatively long landing fields, no ship has been developed which satisfactorily permits vertical rising and landing.

An important object of the present invention 20 is to provide an airplane embodying novel principles of operation which permit the development of the necessary differential sustaining pressures on the upper and lower surfaces of the plane without any forward movement of the ship.

A further object is to provide an airplane having a power source which is operative when the plane is at rest for generating a sufficient lift to cause the plane to rise from the ground, and wherein the power source is operative for imparting forward movement to the plane.

A further object is to provide novel balanced propelling means operative for materially reducing pressures adjacent the upper surfaces of the plane to impart a lifting force thereto for moving the plane horizontally, and to provide means for unbalancing the propelling forces to effect forward movement of the ship.

A further object is to provide means for varying the reduction in air pressures above the ship 40 to effect lateral stabilization thereof.

A further object is to provide a vertically movable stabilizer operative when the ship is not moving forwardly to effect longitudinal stabilization.

A further object is to provide an airplane having propellers adapted to act in opposition to each other to effect a reduction in pressure therebetween and to utilize such pressure reduction to assist in sustaining the plane, and to provide 50 means for utilizing the propellers to move the ship forwardly without changing the positions or directions of rotation of the propeller.

Other objects and advantages of the invention 55 will become apparent during the course of the following description.

In the drawings I have shown several embodiments of the invention. In this showing,

Figure 1 is a front elevation of a plane embodying one form of the invention.

5

Figure 2 is a side elevation of the same,

Figure 3 is a plan view,

Figure 4 is a section on line 4—4 of Figure 3, the rear structure of the ship being omitted,

Figure 5 is a similar view taken substantially on line 5—5 of Figure 3,

10

Figure 6 is a similar view on line 6—6 of Figure 3,

Figure 7 is a sectional view similar to Figure 5 showing a somewhat modified form of plane,

15

Figure 8 is a detail view of one form of propeller,

Figure 9 is a plan view of a further modified form of ship, and,

Figure 10 is a front elevation of the same.

20

Referring to Figures 1, 2 and 3, the numeral 10 designates the body of the ship having oppositely extending wings 11 connected thereto. The body 10 forms the fuselage of the ship and may be supported on the ground in any suitable or conventional manner, such as by the use of forward landing wheels 12 and a tail skid 13.

25

The body 10 is in the form of a longitudinally extending tube having a passageway 14 extending throughout its length and open at both ends. The passage 14 forms a tunnel and at opposite ends of this tunnel are arranged forward and rear propellers 15 and 16 of types to be referred to later. Referring to Figure 4, the propellers are shown as being driven by suitable motors 17 and 18 supported in the tube 10 by suitable supporting frames 19.

30

The wings 11 are hollow, as shown in Figures 5 and 6 and communicate with the interior of the tube 10 through openings 20. These openings are controlled by shutters 21 so that the relative degree of communication between the two wings 11 and the tube 10 may be varied for a purpose to be described. The controls for the shutters have not been shown in detail, but it will be noted that each shutter is pivoted as at 22 and may be provided with a crank arm 23. The crank arms of the shutters at each side of the tube 10 are preferably connected together for simultaneous operation.

35

Referring to Figures 3, 5 and 6, it will be noted that each wing 11 is provided with a plurality of suitably distributed openings 24 toward the forward portions of the wings and preferably elongated openings 25 are arranged rearwardly of the openings 24. All of these openings are provided

45

50

55

for the same purpose, and the reason for distributing them will become apparent. Each of the upper wing openings 24 and 25 is provided with a plurality of shutters 26, and each shutter is pivoted as at 27. Each shutter is further provided with an operating arm 28, and the arms of each set of shutters are connected by a link 29. The forward end of each link 29 is connected by a link 30 to one end of an arm 31 rotatable by a shaft 32, and the various shafts 32 are connected together for simultaneous operation from the cockpit in any desired manner.

The fuselage is provided above its forward end with a cockpit or driver's compartment 33 having a window 34 at its forward end. Rearwardly of the cockpit, the fuselage is provided with an elongated recess 35 closed by a top wall 36 and downwardly diverging side walls 37, the latter being illustrated in Figure 5. The wall 36 is provided substantially centrally of its length with a relatively large opening 38, and similar smaller openings 39 are provided adjacent the forward and rear ends of the wall 36. Each opening 38 and 39 is provided with a plurality of shutters 40 each of which is pivoted as at 41 and provided with a depending arm 42. The lower ends of the arms 42 of each set of shutters 40 are connected by a link 43 and each of these links is pivotally connected to the upper end of an arm 44 carried by a rod 45 extending forwardly into the cockpit and controlled by a suitable operating lever 46. The lever 46 also is preferably connected to the shafts 32 previously described whereby the shutters 26 of the wings and the shutters 40 of the top of the fuselage will be simultaneously opened and closed upon operation of the lever 46.

The forward end of the fuselage adjacent the driver's compartment is curved or sloped downwardly as at 47, and beneath the wall 47 is arranged a hood 48. The hood 48 is connected at its ends to a shaft 49 having an operating arm 50 within the tube 10. A similar hood 51 is arranged rearwardly of the fuselage, and is normally disposed within the recess 35. The rear hood 51 is connected at its ends to a shaft 52 having an arm 53 depending therefrom. The arms 50 and 53 are connected by a link 54 for simultaneous operation. Such operation may be effected by a rod 55 projecting downwardly from the driver's compartment and connected at its lower end to an arm 56 extending rearwardly from the shaft 49.

The wings 11 are provided with the usual ailerons 57 which are employed only when the ship is moving forwardly, and these ailerons are subject to conventional control. A stern structure 58 projects rearwardly of the fuselage and carries stabilizers 59 and a rudder 60. These elements also are subject to conventional control, but they are not employed when the ship is rising or landing vertically inasmuch as their operation obviously depends on horizontal motion of the ship. In stationary flight, lateral stabilization is secured by controlling the shutters 20 in a manner to be described while longitudinal stabilization is accomplished through a stabilizer 61 arranged at the rear end of the fuselage and controlled by a lever 62 having suitable connection with the stabilizer in any suitable manner.

The form of the invention shown in Figure 7 is similar to the form previously described except that it is intended for use in lighter plane structures and does not employ the wing openings 24 and 25 and their controlling shutters. In Figure 7, it will be noted that a tube or fuselage

63 is employed but does not communicate with the interior of the wings 64. This form of the invention is otherwise similar to the form previously described including the use of the fuselage shutters 40, etc. Since there is no communication between the fuselage and the interior of the wings, the stabilizing openings 20 are not employed, but openings 65 are provided in opposite sides of the bottom of the fuselage and these openings are controlled by suitable shutters 66 each of which is pivoted to a shaft 67 having an operating arm 68. The arm 68 may be suitably controlled from the driver's compartment.

A further modified form of the invention is shown in Figures 9 and 10, and except for the features to be referred to, this structure is similar to the plane shown in Figures 1 to 6 inclusive and need not be referred to in detail. The only differences involved lie in the provision of dual tunnels or fuselages 69 each of which is similar to the fuselage 10 except that the top wall 36 extends throughout the length of each fuselage. The driver's compartment may be made substantially longer as at 70 and is arranged centrally of the width of the ship.

As will become apparent, conventional propellers of the fixed blade type cannot be employed with the present invention. The forward propellers 15 are of the variable pitch reversible type, while the rear propellers 16 are variable in pitch, but need not be reversible. The present invention does not relate to the propellers per se, and any satisfactory types of reversible and variable pitch propellers may be employed. One such propeller has been illustrated conventionally in Figure 8 as comprising a hub 71 and blades 72. Each blade is provided with a bevel gear 73 meshing with a third bevel gear 74 which may be rotated in any suitable manner to alter the pitch of the blades or to reverse the pitch when the propeller is used at the forward end of the ship. As previously stated, the propeller in Figure 8 is merely a conventional representation, and any of the well known types of variable pitch and reversible propellers may be used. It also will be apparent that the blades of the propellers will be controlled from the cockpit of the ship.

The operation of the form of the invention shown in Figures 1 to 6 inclusive is as follows:

The motors are placed in operation and when it is desired to take-off, the propellers 15 and 16 are suitably adjusted to pump air outwardly from the tunnel 14. Where one motor is employed amidships with both propellers rotating in the same direction, it will be apparent that the blades of the propeller 15 will be arranged with their pitch opposite and equal to the pitch of the blades 16. Where two motors are employed, they may rotate in the same or in opposite directions, and in the latter case, the blades of the propellers 15 and 16 will be similarly and equally pitched since they will be rotating in opposite directions.

Under the conditions referred to, it will be apparent that the propellers will have no longitudinal propelling effect on the ship since their horizontal reactions will be equal. Prior to taking-off, the aviator will open all of the shutters 26 and 40, thus affording communication between the fuselage and the interiors of the recess 35 and wings 11. The pumping of air from the tunnel 14 by the oppositely acting propellers materially reduces the pressure in the tunnel, and this pressure is communicated to the recess 35 and to the interiors of the wings 11. Thus air will be drawn downwardly through the shutters 26 and 40 to

materially reduce the pressure adjacent the upper surfaces of the plane, thus creating the same effect as is present with a conventional airplane in horizontal flight. In other words, differential lifting and sustaining pressures will be created above and below the plane, whereby the air pressure beneath the plane will cause it to rise vertically.

The total lifting force developed will depend upon the pitches and sizes of the propellers, and the speed of rotation, and in flight, the pitches and speed of rotation are varied according to the height to which the plane is elevated. When the desired elevation is reached, the operator will slowly reduce the pitch of the blades of the propeller 15, thus slowly and progressively reducing the degree of partial vacuum existing in the tunnel 14 and at the same time causing the propeller 16 to over-balance the propeller 15. The reaction from the propeller 16 accordingly will exceed that of the propeller 15, whereupon the plane will start to move forwardly, and the progressively increasing differential pressures incident to the forward movement of the ship will counteract the progressively decreasing differential pressures occurring through the changing of the pitch of the blades of the forward propeller.

When the blades of the forward propeller have been turned so that their pitch is substantially zero, the plane will be in horizontal flight, at which time the shutters 26 and 40 may be closed. The blades of the propeller 15 then may be turned to correspond in pitch to the blades of the propeller 16 whereby their reactions are added to increase the horizontal speed of the ship. Inasmuch as air will be moving rearwardly through the tunnel 14 at a relatively great velocity under such conditions, the blades of the propeller 16 may be turned to increase their pitch beyond the pitch of the blades of the propeller 15 to increase the reactionary effect of the propeller 16 and further add to the speed of the vehicle.

It will be noted that the use of the hoods 48 and 51 is not essential to the operation of the plane, but their use is desirable to increase the lifting effect as the plane rises vertically from the ground. By swinging the hoods downwardly, the outwardly moving air projected by the propeller when the plane is ready to take-off, strikes against the hood and is deflected downwardly to create a direct vertical reaction tending to lift the plane from the ground.

To secure lateral stabilization, the shutters of the two wings may be separately controlled to vary the effective openings through the wings and thus vary the lifting force on one side of the plane. It is preferred however, that the wing shutters be operated simultaneously with each other and with the shutters 40, and accordingly the shutters 21 are provided. These shutters are normally open and if one wing tends to rise as the plane moves vertically, the shutters 21 on the rising side of the plane are closed or partially closed to reduce the differential pressure acting on the upper and lower surfaces of the rising wing, thus laterally stabilizing the plane. The same effect is secured in the form of the invention shown in Figure 7 by selectively opening and closing the shutters 66, the shutter on the rising side of the plane being opened to reduce the pressure acting beneath such side of the plane. It will be apparent that when the ship is moving horizontally under full headway, lateral stabilization is accomplished through the usual ailerons 57.

When the plane is moving vertically, longitudi-

nal stabilization is secured through the stabilizer 61. If the plane tends to turn upwardly, the stabilizer 61 may be swung downwardly, whereupon pressure from the rearwardly moving column of air from the propeller 16 will cause an upward reaction at the rear end of the plane. If the plane inclines downwardly and forwardly, it will be apparent that the stabilizer 61 will be turned upwardly. During forward flight, however, the stabilizers 59 may be employed to secure longitudinal stabilization, and the stabilizer 61 need not be operated.

From the foregoing it will be apparent that the present invention provides a plane wherein differential elevating and sustaining pressures are secured without any forward motion of the plane, thus permitting the ship to land and take-off vertically. Thus the plane is able to utilize a flying field not substantially larger than its own size. It also will be apparent that after the proper elevation has been attained, the plane is readily caused to move forwardly merely by distributing the counteracting forces of the forward and rear propellers in the manner previously stated. As the plane approaches its landing field, its headway readily may be slackened merely by reversing the adjustment of the blades of the forward propeller so that the ship will be partially sustained through its forward motion and partially through the reduced pressures above the plane when the forward propellers are adjusted in the manner just described and the shutters 26 and 40 are opened. Thus the greatest possible degree of maneuverability is provided.

In the form of the invention shown in Figures 1 to 6 inclusive, a single motor may be used amidships, or forward and aft motors may be employed as shown, depending upon the size and capacity of the plane. Moreover, it will be apparent that the operation of the ship shown in Figures 9 and 10 is identical with the single tunnel type, the forward propellers having their pitches simultaneously changed to secure the desired results.

It is to be understood that the forms of the invention herewith shown and described are to be taken as preferred examples of the same and that various changes in the shape, size and arrangement of parts may be resorted to without departing from the spirit of the invention or the scope of the subjoined claims.

I claim:

1. An aircraft comprising a body including a horizontal tunnel open at its ends, said body being provided with top openings communicating between said tunnel and the atmosphere, means for controlling communication through said openings, sustaining surfaces connected to said body, and propellers arranged within said tunnel adjacent opposite ends thereof and equally and oppositely operative for exhausting air therefrom, the forward propeller having variable pitch reversible blades.

2. An aircraft comprising a body structure including supporting wings and a substantially horizontal longitudinal tunnel open at both ends, said body structure being provided with top openings communicating with said tunnel, and propellers arranged in said tunnel adjacent opposite ends thereof and operative for exhausting air therefrom at equal rates, and means for adjusting one of said propellers to cause the rear propeller to exhaust air at a greater rate than the forward propeller.

3. An aircraft comprising a body structure in-

- cluding hollow supporting wings and a substantially horizontal tunnel extending longitudinally of the aircraft and open at both ends, said wings communicating with said tunnel and being provided with top openings, and propellers arranged in said tunnel adjacent opposite ends thereof and operative for exhausting air therefrom, the forward propeller being provided with variable pitch reversible blades.
10. 4. An aircraft comprising a body structure including hollow supporting wings and a substantially horizontal tunnel extending longitudinally of the aircraft and open at both ends, said wings communicating with said tunnel and being provided with top openings, and propellers arranged in said tunnel adjacent opposite ends thereof and operative for exhausting air therefrom, the forward propeller being provided with variable pitch reversible blades.
15. 5. An aircraft comprising sustaining wings and a hollow body having a longitudinal tunnel therethrough of substantially uniform cross-sectional area from end to end and open at both ends, the aircraft being provided with top openings communicating with said tunnel, and a propeller arranged within said tunnel adjacent each end thereof, said propellers being equally and oppositely operative for exhausting air from said tunnel, the forward propeller having variable pitch reversible blades.
20. 6. An aircraft comprising a body including a horizontal tunnel open at its ends, said body being provided with top openings communicating between said tunnel and the atmosphere, means for controlling communication through said openings, sustaining surfaces connected to said body, and propellers arranged within said tunnel adjacent opposite ends thereof and oppositely operative for exhausting air therefrom, the forward propeller being reversible.
25. 7. An aircraft comprising a body including a horizontal tunnel open at both ends, hollow sustaining surfaces connected to said body and communicating therewith, said body and said sustaining surfaces being provided with top openings for affording communication between said tunnel and the atmosphere, means for controlling such communication, and propellers arranged within said tunnel adjacent opposite ends thereof and oppositely operative for creating the passage of air through said openings for increasing the differential pressure above and below the aircraft tending to sustain it, one of said propellers being reversible.

BYRON B. PHILLIPS.
